UNITED STATES PATENT OFFICE

104,399

DESIGN FOR A SOCKET COVER

Frank M. Gaul, Decatur, Ill., assignor to Faries Manufacturing Company, Decatur, Ill., a corporation of Illinois

Application November 20, 1936, Serial No. 66,038

Term of patent 3½ years

To all whom it may concern:

Be it known that I, Frank M. Gaul, a citizen of the United States, residing at Decatur, in the county of Macon and State of Illinois, have invented a new, original, and ornamental Design for a Socket Cover, of which the following is a specification, reference being had to the accompanying drawing, forming part thereof,

The figure is a side elevation showing my new design of a socket cover which is circular in cross-section, the other side (not shown in the drawing) is the same as the one shown in elevation.

I claim:

The ornamental design for a socket cover, as shown and described.
